UNITED STATES PATENT OFFICE

FRANK L. BAMFORD, OF DETROIT, MICHIGAN, ASSIGNOR TO C. M. HALL LAMP COMPANY,
OF DETROIT, MICHIGAN, A CORPORATION OF MICHIGAN

LAMP

Application filed July 26, 1926. Serial No. 125,045.

The invention relates to electric lamps and has particular reference to combination lamp assemblies for use upon motor vehicles. One of the objects of the invention is to provide a combination lamp having a tail light and a backing light which are electrically connected to the battery of the motor vehicle by a single wire instead of a pair of wires, thereby reducing the cost of installation and also 10 the fire hazard. Another object resides in the improved mounting for the lights. With these as well as other objects in view, the invention resides in the novel features of construction and combinations and arrangements of parts as more fully hereinafter set forth.

In the drawings:—

Figure 1 is a diagrammatic view of a motor vehicle having a combination lamp and 20 wiring system embodying my invention;

Figure 2 is a rear elevation of the combination lamp;

Figures 3 and 4 are cross sections on the 25 lines 3—3 and 4—4, respectively, of Figure 2;

Figure 5 is a rear elevation of a portion of the lamp;

Figure 6 is a semi-diagrammatic view 30 showing the wiring diagram for the several lamps of the construction.

The combination lamp, as shown particularly in Figures 2, 3 and 4, has the casing 1 with an open rear end and the cover 2 carrying the lens 3 for closing the casing, 35 both the casing and cover being preferably formed of sheet metal. 4 and 5 are substantially parallel partitions within the casing for dividing this casing into three compartments. These partitions, as shown, form the 40 wings of a U-shaped sheet metal member, the base of which is secured to the front wall of the casing by suitable means such as the screws 6. 7 are screws extending through the base of this U-shaped member and the front wall of the casing and preferably having their heads soldered to the base, these screws being used in mounting the casing upon the support therefor. The rear end of the partitions 4 and 5 have the transverse 45 foot flanges 8 and 9, respectively, which are

apertured for the passage of the screws 10 used in securing the cover 2 to the casing.

11 is a tail light located within the central compartment and 12 and 13 are respectively a backing light and stop light located in the 55 end compartments. The tail light is located below the backing and stop lights and near the bottom of the casing, which has an opening closed by the lens 14 for allowing the light rays to pass from the tail light to 60 points below the casing to illuminate the license plate. The tail light is mounted within the metallic socket 15 and is formed in the usual manner so that one terminal of its filament extends axially of its base while 65 the other terminal is formed by the metallic shell surrounding the base, this shell being in electrical contact with the socket. 16 is an insulator plug extending through the front wall of the casing and the base of the 70 U-shaped member secured to this wall and 17, 18 and 19 are electrical conductors extending longitudinally through this insulator plug. 20 is a resilient metallic strap secured to the conductor 19 and extending 75 within the socket 15 into position to be engaged by the central terminal of the tail light 11 when the latter is secured in its socket.

The backing light 12 is electrically insulated from the casing 1 and as shown its mounting comprises the insulator 21 which extends through the partition 4 and is secured thereto. This plug has an opening therethrough for the base of the backing 80 light and is provided with longitudinally extending diametrically opposite grooves 22 for permitting the passage therethrough of the outwardly extending diametrical pins 85 23 formed upon the shell of the base, this 90 shall also forming a terminal of the light filament. The inner face of the insulator 21 is provided with the diametrically extending grooves 24 for receiving these pins and normally holding the light from rotation. 95 25 is a resilient metallic strap secured to the conductor 19 and positioned for yieldable engagement by the central terminal of the backing light and 26 is another resilient 100 metallic strap which is secured to the con-

ductor 17 and is positioned so that it yieldably engages the other terminal of the backing light. With this arrangement it will be seen that the backing light may be readily assembled in its mounting or disassembled therefrom and that when it is assembled its terminals are electrically connected to a pair of conductors extending through the insulator plug upon the lamp casing.

16 The stop light is constructed in the same manner as the tail and backing lights with the shell surrounding its base provided with diametrically oppositely extending pins engageable in bayonet slots formed in the partition 5. The central terminal of this stop light is electrically connected to the conductor 18 by means of the resilient metallic strap 27.

17 The invention further contemplates the provision of means for automatically completing the electric circuit through the backing light upon actuation of the reverse mechanism of the vehicle without however running an electrical conductor direct from the battery to the reverse mechanism. Heretofore, it has been customary in electrical systems where one terminal of a lamp has been grounded, to provide an automatically actuated switch in the "hot" conductor running from the battery to the lamp bulb. Where a construction of this character is associated with a reverse mechanism with the switch in a position to be operated by the reverse mechanism, difficulty is experienced in preventing a short circuiting of the system particularly where the "hot" conductor is adjacent or connected to the reverse mechanism. The present invention eliminates this difficulty by mounting the automatic switch in the ground conductor of the system so that no hot conductor is connected to the reverse mechanism. For accomplishing this result, the following structure is provided

18 As shown diagrammatically in Figure 1, 28 is the frame of the motor vehicle, 29 the storage battery mounted upon the frame and having one terminal grounded upon this frame as by means of the wire 30. The other terminal is adapted to be electrically connected to the stop light 13 as by means of the wire 31 upon closing the switch 32 by actuation of the brake pedal 33. For electrically connecting the tail light and the backing light I have provided a single wire 34 leading from the other terminal of the battery 29 to the lamp casing and adapted to be electrically connected to the conductor 19, there being, of course, the manually operable switch 35 for turning on or off the tail light. Since the lamp casing is grounded upon the frame 28 current will flow through the wire 34 when the switch 35 is closed, the filament of the tail light 11 and the frame, thus completing the circuit. To

complete the circuit for the backing light I have provided the wire 36 which leads from the terminal 17 to the yieldable contact member 37 which is mounted upon and insulated from the change-speed gearing 38 having the reverse mechanism for propelling the motor vehicle in a rearward direction. This contact member is positioned to be yieldably engaged by the shifter rod 39 when the latter has been shifted to operative position for propelling the motor vehicle in the rearward direction and as a consequence when this shifter rod is in this operative position the circuit is completed for the backing light. Furthermore, with this arrangement the backing light uses no electric current unless the tail light is in use, so that a saving of the electric current is possible during the day time. Still further the mounting of the switch 37 in the ground line of the circuit including the lamp 12, eliminates the necessity of running a "hot" conductor to the reverse mechanism, with the result that any break in the conductor leading to the reverse mechanism only causes the backing lamp to light without short circuiting the entire system.

What I claim as my invention is:

1. In a motor vehicle having a frame, a battery and reverse mechanism electrically grounded upon said frame, a lamp casing having a tail filament and a backing filament, means for electrically grounding one terminal of said tail filament upon said frame, means for electrically insulating both terminals of said backing filament from said frame, means for electrically connecting one terminal of said backing filament to said reverse mechanism when in operative position, a single wire from said battery to said lamp casing, and means within said casing for electrically connecting said wire to the other terminals of said tail and backing filaments.

2. In a motor vehicle having a frame, a battery and reverse mechanism electrically grounded upon said frame, a combination lamp having a casing electrically grounded upon said frame, a tail light within said casing having one terminal electrically grounded upon said casing, a backing light within said casing, means for electrically insulating the terminals of said backing light from said casing, an insulator plug mounted upon said casing, a pair of electrical conductors extending through said plug, a single wire from said battery to one of said conductors, means for electrically connecting said conductor to the other of the terminals of said tail light and to a terminal of said backing light, means for electrically connecting the other of the terminals of said backing light to the other conductor and a wire connected to said last-mentioned conductor and adapted to be electrically con-

nected to said reverse mechanism when the latter is in operative position.

3. In a combination lamp, a casing, an insulator plug mounted upon said casing, a pair of electrical conductors extending through said plug, a light within said casing and having a terminal electrically connected thereto, a second light within said casing, an insulator upon said casing for carrying said second light, means extending from one of said conductors to the other terminal of said first-mentioned light and to a terminal of said second-mentioned light for electrically connecting the same and means extended from the other terminal of said second-mentioned light to the other of said conductors for electrically connecting the same.

4. In a combination lamp, a metallic casing having a pair of compartments therein separated by a partition, an insulator plug extending through said casing into one of said compartments, a metallic socket within said last-mentioned compartment and in contact with said casing, a light mounted in said socket and having an outer terminal electrically connected thereto, a second light within the other of said compartments, an insulator socket mounted upon the partition between said compartments and carrying said second light, a pair of electrical conductors extending through said plug, resilient straps connected to one of said conductors and positioned for yieldable engagement with the center terminals of said lights and another resilient strap connected to the other of said conductors and positioned for yieldable contact with the outer terminal of said second-mentioned light.

5. In a lamp, the combination with a metallic casing of an insulator plug extending therethrough, a pair of electrical conductors extending through said plug, a light having a base with diametrically outwardly extending pins, an insulator mounted upon said casing and apertured to receive said base, the wall of the aperture having longitudinally extending diametrically opposite grooves for permitting the passage of said pins therethrough and resilient connectors secured to said conductors and positioned for yieldable engagement with the terminals of said light when engaged in said insulator.

6. In a combination lamp, a casing, a pair of electrical conductors extending into said casing and insulated therefrom, a lamp bulb within said casing and having a terminal electrically connected thereto, a second lamp bulb within said casing, means insulating said second lamp bulb from said casing, means extending from one of said conductors to the other terminal of said first mentioned lamp bulb and to a terminal of said second mentioned lamp bulb for electrically connecting the same, and means ex-

tending from the other terminal of said second mentioned lamp bulb to the other of said conductors for electrically connecting the same.

In testimony whereof I affix my signature. 70
FRANK L. BAMFORD.
